PRESETTABLE IMPULSE REGISTER

Leslie B. Haigh, West Orange, and Franklin A. Stearn, Westfield, N. J., assignors to Federal Telephone and Radio Corporation, New York, N. Y., a corporation of Delaware

Application March 2, 1946, Serial No. 651,667

4 Claims. (Cl. 235—132)

1

The present invention relates to an impulse register or electric counter particularly to be used in connection with a signalling or other device to be actuated upon the recordation of a predetermined number of impulses.

An object of the present invention is to provide an impulse register arrangement which registers a predetermined number of impulses or closures of a circuit such as may be controlled by a switch to occur before a signalling device or the like is actuated.

It is another object of the present invention to provide means for pre-setting for the reception of a predetermined number of impulses or the occurrence of a predetermined number of switch closures before it effects a desired operation.

It is still another object of the present invention to provide means for immediate operation of a signalling or other device upon reaching a predetermined counting or registering position without any operation of electrical or mechanical elements.

It is still another object of the present invention to provide means for a fixed actuating position of the impulse register and a variable predetermined starting position.

It is also an object of the present invention to provide multiple precautionary means in order to guard against premature actuation right up to the moment of the actuating impulse.

It is still an object of the present invention to provide means for indicating that the properly prepared setting of the impulse register has been effected.

With these and other objects in view the present invention will become apparent and clearly understood in connection with the following specification and accompanying drawing which discloses a circuit for the impulse register or electric counter.

Referring now to the drawing, the impulse register comprises a conventional ratchet-driven, step-by-step selector switch controlled by an electromagnetic stepping mechanism 1. A rotor 2 carries a ratchet wheel 3 and, preferably three double-end wipers 4, 5 and 6 which make contact, as the rotor 2 rotates, with successive terminals I to XI in three arcs 7, 8 and 9, respectively. An electromagnet armature 10 is attracted when current flows through the coil 11 and engages the next tooth of the ratchet wheel 3. When current ceases, the armature 10 releases under the influence of a restoring spring 12 and advances the rotor 2 by one step, causing the wipers 4, 5 and 6 to move from one arc terminal to the

next. An interrupter spring 13 opens contact when the armature 10 is almost fully attracted.

A second, holding relay 15 which operates at particularly high speed has an armature 16 which is attracted to close a contact 17 when current flows through the coil 18 of the relay 15. A conventional tap switch 19 is equipped with a contact arm 20 which may be set manually upon any desired one of a number of contacts I to XI disposed in an arc 21. A battery 22 having a positive pole 23 and a negative pole 24, provides power to energize the coil 11, as well as the coil 18, to actuate or energize the electric device which is inserted into the circuit, and also to light signal lamps, said device and the purpose of the signal lamps to be described later.

The selector switch, the tap switch 19, the holding relay 15, one of the mentioned lamps and the battery 22 are preferably housed in one container which should be preferably as compact and light in weight as possible. Accordingly, the selector switch is preferably designed to operate from a battery of two primary cells. The holding relay 15 is of a known type of high speed operating relays and is exceptionally rapid in operation for a purpose to be explained later.

The impulse register can be arranged for operation by any momentarily actuated switch wherein a contact is closed for only a very short interval. To this end two terminals preferably in the form of pin jacks 25 and 26 are provided to which line wires leading to a switch contact 27 may be connected by means of pin plugs 28 and 29.

The impulse register is also designed to be connected to and at the proper time to actuate a signalling device 30 which is protected against premature actuation at all times. The device 30 is accordingly mounted in a separate adapter unit arranged for connection to the impulse register through a plug and jack connection. For example, the register is provided with a plug 31 having conventional tip and sleeve contacts 32 and 33, respectively, and the adapter unit carrying the signalling device 30 is provided with a jack 34 having a tip spring 35, a sleeve 36 and an auxiliary break spring 37 normally in electrical contact with the tip spring. The adapter unit is wired, as shown in the circuit diagram in the drawing, in such a way that the device 30 is short circuited and thus protected against premature operation until such time as jack 34 is engaged with plug 31 and the contact between the springs 35 and 37 is opened.

A dummy unit 38, of a construction similar to that of the adapter unit carrying the device 30,

is also provided and comprises an alarm lamp 39 and a jack 40, having a tip spring 41 and a sleeve 42. The jack 40 can be engaged with plug 31 of the register in place of jack 34 of the signalling device adapter unit when it is desired to preset the operating condition of the register, as will be described later. When the jack 40 is so engaged with the plug 31, a projection 39' on the dummy unit 38, which has no counterpart on the signalling device adapter unit, engages mechanically with a stud 43 of a spring switch 44, closing contacts 45-45' and 46-46' for a purpose which will be explained later.

The impulse register is further designed to cause the operation of the device 30 as a direct and immediate result of the closure of the switch contact 27 and to count, and render ineffective to cause actuation, a predetermined number of prior closures, which may be any number preferably between 0 and 10, determined by a presetting of the position of the wiper 5 in conjunction with a setting of the arm 20 of the tap switch 19. The circuit diagram shows the wiper 5 contacting, by example, terminal I of arc 8, in which condition the register is preset to count, and render ineffective to cause energization of device 30, nine closures of the switch contact 27, and to cause energization at the tenth closure of the latter, when the plugs 28 and 29 are engaged with the jacks 25 and 26, respectively, and plug 31 with jack 34.

The operation of the circuit to perform these functions takes place in the following manner:

At the first closure of the switch contact 27, a circuit is closed via the coil 18 of the holding relay 15 and via coil 11 of the stepping mechanism, which may be traced from the positive pole 23 of the battery 22, wire coils 11 and 18 in parallel arrangement, terminal I of the arc 8, wiper 5, jack 25, plug 28, switch contact 27, plug 29, jack 26 to the negative pole 24 of the battery 22. The holding relay 15 attracts its armature 16 and closes a locking circuit for its coil 18 and another circuit for coil 11, which circuit is independent of the circuit through the switch contact 27, namely from the positive pole 23 of the battery 22, via coils 11 and 18 again in parallel arrangement, to the contact 17, armature 16, interrupter spring 13, contact 14, back to the negative pole 24 of the battery 22.

The holding relay 15 is preferably designed to operate within a time of the order of one millisecond after closure of a current path through its coil in order to guarantee its operation in response to a closure of the switch contact 27 of very short duration. The stepping mechanism 1 may, on the other hand, be of the type in which a delay of the order of 20 milliseconds occurs between the closure of a current path through its coil 11 and the attraction of its armature 16, inasmuch as current is maintained through the coil 11 by means of the holding relay 15, even though contact 27 may have opened again.

However, when the armature 16 of the stepping mechanism 1 has been attracted, the interrupter spring 12 opens the contact 14, and if contact 27 is at this moment open or when it opens, current ceases in the coils 11 and 18 and the armatures 16 and 10, respectively, are released. The return movement of the armature 16 due to the spring 12 advances the ratchet wheel 3 and the wipers 4, 5 and 6, which are ganged with the ratchet wheel 3, move to respective terminals II of the arcs 7, 8 and 9, respectively.

As the result of a second and subsequent mo-

5
4
mentary closure of contact 27 the above described operations are repeated and the respective wipers 4, 5 and 6 moved accordingly to the terminals III of the respective arcs 7, 8 and 9 and to the subsequent terminals until, as the result of a ninth closure, the wipers move to the terminals X.

During these operations, not only has no intended path been closed through the device 30, but the device has been short-circuited and so protected against premature actuation by transient or stray induced current, in a circuit which may be traced from the device 30, wire sleeve 36, sleeve contact 32, successive terminals I thru IX of the arc 7 or terminal XI of the arc 7, wiper 4, tip contact 33, tip spring 35, spring 37, to the device 30. To render the short circuit continuously effective even during the movement of the wiper 4, the latter is preferably of the "bridging" type which when moving from one terminal to the next makes contact with the second terminal before breaking contact with the first.

When the wipers 4, 5 and 6 are standing on the terminals X of the arcs 7, 8 and 9, respectively, the operating circuit for the coils 11 and 18 is open at the wiper 5 and the short circuit around the device 30 is open at the wiper 4. The impulse register is now in the operating condition and the next closure of the switch contact 27 will cause actuation of the device 30. When the switch contact 27 closes for the tenth time, a current path is closed through the device 30 from the positive pole 23 of the battery 22, wire tip contact 33, tip spring 35, signalling device 30, sleeve 36, sleeve contact 32, terminal X of the arc 8, wiper 5, jack 25, plug 28, switch contact 27, plug 29, jack 26, and back to the negative pole 24 of the battery 22.

Thus, nine successive momentary closures of the switch contact 27 have been counted and rendered ineffective to cause actuation of the device 30, whereas at the tenth closure the device 30 is immediately energized.

If it is desired that the actuation of the device 30 be effective, for example at the ninth closure of the switch contact 27 instead of at the tenth, as described above, the impulse register is preset in a manner to be described, so that the wipers 4, 5 and 6 are standing on respective terminals II instead of respective terminals I. It will be evident from the foregoing disclosure that from this condition eight successive momentary closures of the switch contact 27 will cause the wipers 4, 5 and 6 to advance to the respective terminals X and during the advancement will not cause actuation of the device 30, whereas at the ninth closure the latter will be immediately actuated. Similarly, if the wipers 4, 5 and 6 are preset to the respective terminals III, IV . . . or X the device will be energized at the eighth, seventh . . . or first closure, respectively, whereas if the wipers 4, 5 and 6 are preset to terminals XI it will require eleven closures before energization occurs.

It is to be noted that the control or energizing circuit within the impulse register, which is prepared for advancing the wiper 5 to a selected terminal, and which extends from the jack 25 via wiper 5 and terminal X, to the sleeve contact 32, is as direct as possible and includes a minimum of contacts, thus assuring a maximum efficacy of the circuit at the moment of energization. In this connection it is important to emphasize that no relays or other electrical elements are operated in the control circuit. This condition is achieved by providing the wiper 5 with a fixed control position and a variable "starting"

position, to which it is preset according to the number of closures to be counted.

The impulse register can be preset, as stated, in such a way as to cause actuation of the device 30 at the first closure of the switch contact 27, at the eleventh closure, or at any intermediate closure, as desired. In order to effect this presetting, the arm 20 of the tap switch 19 is set upon the contact numbered to correspond to the particular closure at which actuation of device 30 is to occur. The jack 40 of the dummy unit 38 is first engaged with the plug 32 and the jack 40 is disengaged from the plug 42 after the glowing of a signal lamp 47, which is inserted between the wiper 6 and the connecting lead of the jack 26 with the negative pole 24 of the battery 22, has been observed. The impulse register is then preset and the operation of the circuit to perform these functions is as follows:

If it is assumed, for example, that the actuation is to occur at the tenth closure, the contact arm 20 of the tap switch 19, is accordingly set on terminal X of the arc 21, as shown in the drawing. If it is further assumed that the wipers 4, 5 and 6 are standing on any terminals of the arcs 7, 8 and 9 except at terminals XI, as soon as the jack 40 of the dummy unit 38 is engaged with the plug 31, and the contacts 45 and 46 of the spring switch 44 are closed, as explained above, a circuit is closed for the coil 11 of the stepping mechanism 1 from the positive pole 23 of the battery 22 via coil 11, contacts 45 and 46, interrupter spring 13, contact 14, to the negative pole 24 of the battery 22. A similar circuit is closed for the coil 18 of the holding relay 15, but the latter has no useful function at this stage. The armature 10 of the stepping mechanism 1 becomes attracted and the spring 13 opens a contact 14 and thereby opens the circuit just traced. The armature 10, therefore, releases again and advances the ratchet wheel 3 and the wipers 4, 5 and 6 move to the next adjacent terminals. The spring recloses the contact 14 and the circuit for the coil 11. The cycle repeats itself and the wipers advance thereby step-by-step until they are standing on the terminals XI. At this moment, coil 11 is once more energized in the circuit already traced and the armature 10 is attracted again but this time it remains attracted, since coil 11 is maintained energized, despite the opening of the contact 14 in a circuit from positive pole 23 of the battery 22, coil 11, contact 45, contact arm 20, terminal X of the arc 21, terminal XI of the arc 9, wiper 6, signal lamp 47 back to the negative pole 24 of the battery 22. The current through the lamp 47 causes it to glow as an indication to the operator that the jack 40 may be disengaged from plug 31. When this disengagement is effected, the contacts 45 and 46 are opened and the holding circuit for the coil 11 opens at the contact 45, the armature 10 releases and the wipers 4, 5 and 6 move to the respective terminals I. The impulse register is now preset to cause energization of the device 30 at the tenth closure of the switch contact 27, as already stated and illustrated.

Had the wipers 4, 5 and 6 been standing upon the respective terminals XI at the beginning of the presetting operation, described by way of example, the armature 10 would have become attracted by reason of the energization of the coil 11 in the circuit, including the contacts 45 and 46, and would have remained attracted due to the immediate presence of another circuit, traced above, including the lamp 47. The armature 10 would have been released and the wipers 4, 5 and

6 would have been moved to terminals I upon disengagement of jack 40 from the plug 31, thus completing the presetting operation as before.

If it is desired to preset the register for actuation of the device 30 at, for example, the ninth closure instead of the tenth, the arm 20 is set upon terminal IX of arc 21, instead of the terminal X. The advance of the wipers 4, 5 and 6 will then be arrested in the terminals I instead of terminals XI by reason of a circuit for maintaining the coil 11 energized, which may be traced from the positive pole 23 of the battery 22 via coil 11, contact 45, contact arm 20, terminal IX of the arc 21, terminal I of the arc 9, wiper 5, lamp 47, back to the negative pole 24 of the battery 22. Upon disengagement of the jack 40 from the plug 31, the wipers 4, 5 and 6 move to the respective terminals II and the impulse register will then be preset for actuation of device 30 at the ninth closure of the switch contact 27, as already stated and illustrated above. Similarly, if the contact arm 20 is set upon any other terminal of the arc 21, it will be evident that the impulse register may be preset for discharge at the particular closure, each corresponds to the number of the terminal.

In order to provide an additional safeguard against premature operation of the device 30, an alarm lamp 39 is provided in the dummy unit 38. If, at any time, during the presetting operation, and for any reason, spurious voltage should be present between the tip contact 33 and the sleeve contact 32, of the plug 31, it is manifested by glowing of the lamp 39. The presetting operation may be repeated as often as it is deemed desirable. The continuity of the lamp 39 can be verified before the desired presetting of the impulse register by setting the arm 20 upon terminal XI engaging jack 40 with plug 31, awaiting the glowing of the lamp 47 which will occur when the wiper 6 reaches the terminal X and then closing the contact 27. The lamp 39, if operative, will then glow in a circuit from the positive pole 23 of the battery 22, via tip contact 33, tip spring 41, lamp 39, sleeve 42, sleeve contact 32, terminal X of the arc 8, wiper 5, jack 25, plug 28, contact 27, plug 29, jack 26, and back to negative pole 24 of the battery 22.

While we have disclosed the principles of our invention in connection with a single embodiment, it will be understood that this embodiment is given by way of example only and not as limiting the scope of the invention as set forth in the objects and the appended claims.

What we claim is:

1. In an impulse register circuit, a stepping member, a first and a second arc and a rotor having a ratchet wheel and a wiper for each of said arcs, a relay operating said rotor by means of said ratchet wheel, output terminals, the first wiper short circuiting said output terminals up to a predetermined terminal, a first switch connected with the wiper of said second arc and said relay connected with the terminals of said second arc, the latter being adapted to conduct the pulses from the first switch to the said relay and at a predetermined terminal of the second arc to conduct the first switch connection directly to the said output terminals.
2. In an impulse register circuit, a stepping member comprising a first, a second and a third arc, a plurality of terminals on each of said arcs, a rotor having a ratchet wheel and a wiper for each of said arcs, a relay having a coil operating said rotor by means of said ratchet wheel, output

terminals, said first arc short circuiting said output terminals up to a predetermined terminal, a first switch connected with the wiper of said second arc, and said relay coil being connected with said second arc, the latter being adapted to conduct the pulses from said first switch to the said relay coil and at a predetermined terminal of the second arc to conduct the first switch connection directly to the said output terminals, a tap switch connected with said third arc, a second switch connected with said third arc, said tap switch being adapted to set a predetermined number of impulses to be received by said stepping member until connection with the output terminals is achieved.

3. In an impulse register circuit, as set forth in claim 2, means for presetting said tap switch to position said wiper a selected number of steps away from said predetermined terminal, and means to indicate when said wiper is in a desired preset condition.

4. In an impulse register circuit for energizing a control circuit, a plug, a first jack having contact springs adapted to be operated upon the insertion of said plug, a second jack connected to said control circuit, a rotary step by step switch having no normal position, first, second and third terminal arcs for said switch, a wiper for each of said arcs, a magnet including contacts for advancing said wipers over said terminals, a relay, an impulse sender, a signal, a manually operable indicating switch, the terminals of said indicating switch being connected to the terminals 25 30

nals of said first arc, a first circuit including said signal, said first arc, said indicating switch, said first jack, said plug, said magnet and said relay for stepping said wipers to the terminal position corresponding to the position of said indicating switch when said plug is inserted in said first jack and for displaying said signal, a second circuit including said second arc, to one terminal of which one conductor of said plug is connected, said third arc for short circuiting the conductors of said plug in all terminal positions except the one position in which said second arc is connected to one of the conductors of said plug, and said impulse sender, the said control circuit being energized only after said plug is inserted into said second jack and a number of impulses as determined by the position of said indicating switch have been transmitted by said impulse sender.
